UNITED STATES PATENT OFFICE.

MAURICE O. SMITH, OF ST. LOUIS, MISSOURI.

VAPORIZER.

Application filed January 26, 1920. Serial No. 354,150.

To all whom it may concern:

Be it known that I, MAURICE O. SMITH, a citizen of the United States, and a resident of the city of St. Louis and State of Missouri, have invented certain new and useful Improvements in Vaporizers, of which the following is a specification containing a full, clear, and exact description, reference being had to the accompanying drawings, forming a part thereof.

My invention relates to improvements in vaporizers, and has for its primary object a vaporizer especially adapted for internal combustion engines, whereby a heavy oil can be vaporized and used as a combustion agent.

A further object is to construct a device in which the intake and exhaust manifolds are combined in one casting with the additional provision that the direction of the exhaust gases can be controlled.

In the drawings,

Fig. 1 is a side elevation of my device;

Fig. 2 a longitudinal cross section;

Fig. 3 a vertical cross sectional view taken on the line 3—3 of Fig. 2;

Fig. 4 a perspective view of the valve made use of for controlling the flow of exhaust; and

Fig. 5 a cross sectional view taken on the line 5—5 of Fig. 2.

In carrying out my invention, I employ the manifold 6, this manifold being provided with the exhaust openings 7 and the intake openings 8. The intake openings 8 are connected together by a passage 9 which opens into a cup or bowl 10, this cup 10 being connected to the carburetor of an internal combustion engine by means of the pipe 11.

Opening into the passageway 9 is secured a priming valve 12, the object of this is to permit the introduction of gasoline into the cup or bowl 10 or in other words prime the engine. The manifold 6 is closed at one portion by the plate 13 so as to expose the cup 10. My object in exposing this cup is that when any carbon is lodged on the cup the same can be either burnt off or removed by scraping.

The intake manifold is partially surrounded by the exhaust manifold as is also the cup 10. My object in combining the intake and exhaust is so that the fuel mixture from the carburetor is superheated before being taken into the cylinder. In this

way the explosion takes place more rapidly than if cold gas were admitted, in fact I have found it possible to operate a machine with my vaporizer on ordinary coal oil and filtered crude oil, that is, crude oil from which the sediment has been removed.

The port 7a which is one of the exhaust ports is partially closed by the valve 14, this valve having a tapered surface 15, a rectangular projection 16 and an additional projection 17, the projection 17 being adapted to close the flow of exhaust or regulate it so that all of the exhaust will have to pass in one direction only, or to allow it to pass in two directions. In Fig. 2 this valve is shown as directing the exhaust completely around so that none can escape into the muffler without first passing by the cup. This valve, however, can be so regulated as to leave the upper passage 18 open, and thus divert a certain amount of exhaust directly into the muffler without passing around the cup.

On the face of the valve 14 I provide a series of notches so that the operator of the machine is able to tell whether the valve is open full, half way or closed, and after the valve has been set in the desired position the same is clamped against rotation or accidental movement by means of the arms 19 which are secured to the machine or engine, this being common practice in all internal combustion engines used for motor vehicles for securing the manifold to the engine.

The purpose of the bowl-shaped enlargement 10 is to form a reservoir in which the mixture drawn from the carburetor has time to rest and become thoroughly heated and vaporized before being drawn into the cylinders of the engine, in this way a highly explosive dry gas is formed, which will give a great deal more power than where a moist gas, that is, a mixture which has not been thoroughly vaporized has been drawn into the cylinder. This moist mixture is what is delivered to the cylinders by the ordinary carburetor, and it lodges on the cylinder walls, mixes with the lubricating oil and thins it down, as well as burning slowly on the cylinder walls and causing a carbon deposit. By allowing the mixture to remain in the enlargement 10, which acts as a reservoir since it contains a great deal more mixture than is required for the cylinders, perfect vaporization of the mixture takes

place and consequently the engine develops more power and with a great saving of fuel.

It will be observed from the drawing that the priming cup 12 is provided with an operating handle or rod 12^a for operating the same as desired, and the priming cup may be used for the introduction of gasoline, or other fluid, into the cup or bowl 10, as set forth. It also may be utilized for the admission of air directly into the intake manifold. If air is admitted through this cup or valve it is obvious that additional oxygen will be added to the fuel and thereby increase its efficiency.

16 Having fully described my invention, what I claim is:

1. A vaporizer for internal combustion engines comprising a combined intake and exhaust manifold, the exhaust portion of the 20 manifold having upper and lower passages connected to each other at each end, an enlargement formed in the lower passage approximately at its middle, the intake portion of the manifold being formed integral 25 with the exhaust portion and lying almost wholly within the lower passage, a bowl-shaped enlargement formed integral with the intake portion and lying within the enlargement formed in the exhaust portion, an 30 elbow formed integral with said bowl-shaped enlargement and extending beyond the exhaust portion of the manifold and adapted to having a carbureter attached thereto, a screw threaded outlet formed on 35 one end of the exhaust portion, said outlet normally communicating with both upper and lower passages, a valve located in the upper passage adjacent the outlet for regulating the flow of gases through the exhaust 40 portion of the manifold, means for holding said valve in set position, exhaust and intake ports formed in the manifold for communicating with the exhaust and intake ports of an internal combustion engine, means 45 whereby the bowl-shaped enlargement of the

intake portion may be opened to the atmosphere for the introduction of air directly into the intake portion of the manifold, and means whereby the enlargement of the exhaust portion of the manifold can be opened 50 for cleaning purposes.

2. A vaporizer for internal combustion engines comprising a combined intake and exhaust manifold integrally formed, the exhaust portion of the manifold having upper and lower passages connected together at each end, an enlargement formed in the lower passage of the exhaust manifold midway its ends, an intake portion formed integral with the exhaust portion and lying almost wholly within the lower passage, a bowl-shaped enlargement formed integral with said intake portion and lying within the enlargement formed in the lower passage so that said upper and lower exhaust 65 passages will be of approximately the same area thus preventing back pressure, an elbow formed integral with the bowl-shaped enlargement and extending below the manifold, said elbow provided with a flange for 70 the attachment of a carbureter, a screw threaded outlet formed at one end of the manifold for receiving an exhaust pipe, an adjustable valve located in the upper exhaust passage adjacent the outlet for controlling the passage of gases through said upper and lower passages, means for holding the valve in set position, ports formed integral with the exhaust and intake passages, said ports adapted to correspond with 75 the exhaust and intake ports of an internal combustion engine, a valve controlled means for permitting the introduction of air into the bowl-shaped enlargement of the intake portion, and means for securing said manifold to an internal combustion engine.

In testimony whereof, I have signed my name to this specification.

MAURICE O. SMITH.
